UNITED STATES PATENT OFFICE

105,715

DESIGN FOR A TEXTILE FABRIC

Charles F. Scholle, New York, N. Y., assignor to
The Palmer Brothers Company, New London,
Conn., a corporation of Connecticut

Application July 13, 1937, Serial No. 70,395

Term of patent 7 years

To all whom it may concern:

Be it known that I, Charles F. Scholle, a citizen of the United States, residing at 440 Fourth Avenue, city, county, and State of New York, have invented a new, original, and ornamental Design for a Textile Fabric, of which the following is a specification, reference being had to the accompanying drawings, forming part hereof.

Because of the width of the design, and to avoid the reduction of its elements to too small a scale, I have shown the design in two figures

of which Fig. 1 represents a portion of the design and Fig. 2 the remaining portion which figures are to be assembled by subjoining Fig. 2 to Fig. 1 so that the top of Fig. 2 coincides with the bottom of Fig. 1 so as to show the complete design.

The unitary design is included between the broken lines 1, 1, and 2, 2, beyond which the design, if continued, laterally, repeats.

I claim:

The ornamental design for a textile fabric as shown and described.

CHARLES F. SCHOLLE.
